DESIGN FOR A COMBINATION HOLDER AND EXTRACTOR FOR ELECTRON TUBES OR SIMILAR ARTICLES

Ralph S. Merkle, Emporium, Pa., assignor to Hy-
grade Sylvania Corporation, Emporium, Pa., a
corporation of Massachusetts

Application November 22, 1941, Serial No. 104,264

Term of patent 14 years

To all whom it may concern:

Be it known that I, Ralph S. Merkle, a citizen of the United States of America and residing at 433 Walnut Street, Emporium, county of Cameron and State of Pennsylvania, have invented a new, original, and ornamental Design for a Combination Holder and Extractor for Electron Tubes or Similar Articles, of which the following is a specification, reference being had to the accompanying drawing, forming a part thereof.

The figure is a perspective view of a combination holder and extractor for electron tubes or similar articles, showing my new design.

I claim:

The ornamental design for a combination holder and extractor for electron tubes or similar articles, substantially as shown.

RALPH S. MERKLE.
